UNITED STATES PATENT OFFICE.

GROSVENOR ATTERBURY, OF NEW YORK, N. Y., ASSIGNOR TO STANDARDIZED HOUSING CORPORATION, A CORPORATION OF DELAWARE.

SECTIONAL CEMENTITIOUS STRUCTURE.

1,254,109.

Specification of Letters Patent. Patented Jan. 22, 1913.

Application filed February 15, 1915. Serial No. 8,205.

To all whom it may concern:

Be it known that I, GROSVENOR ATTERBURY, a citizen of the United States, and a resident of the borough of Manhattan, city, 5 county, and State of New York, have invented certain new and useful Improvements in Sectional Cementitious Structures, of which the following is a description.

My invention relates to structures, in the 10 nature of buildings, composed of slabs of concrete or other cementitious material and is of especial value in connection with, though in no way limited to, such structures where the component slabs are of large size, 15 for example, large enough so that a single floor slab may constitute an entire floor of the building, or of a room thereof, and a single wall slab or a comparatively few such slabs placed side by side may constitute an 20 entire wall of a story of the building.

An object of my invention is to provide 25 slabs of the kind referred to, which shall be so formed as to enable them to be easily secured to the adjacent slabs, whether in the same plane therewith or at right angles thereto and so that the joints between the 30 adjacent slabs may be rendered substantially water-tight, without resorting to the tedious and expensive hand operations now in use.

Another object of my invention is to so 35 form the slabs that there will be in the completed structure uninterrupted passages through the walls and floors, which may be used for the installation of pipes, conduits, 40 wires, etc., either during the erection of the structure or at a subsequent time and for the circulation of fluids, such as water, steam, or other liquids or gases, to regulate the temperature of the structure and for similar purposes.

It has been found that under the present 45 practice of joining together adjacent wall slabs of structures, it is almost impossible to prevent a driving rain from leaking through the joints. In order to obviate this difficulty, I have provided the side edges of my improved wall slabs with longitudinal grooves, which coöperate with the corresponding grooves of adjacent slabs to form voids, certain of which are adapted to receive cementitious material to form the joints and certain others of which are adapted to remain open for the drainage of any moisture which may enter the joint through the exterior of the wall and thus prevent the leak-

age of this moisture into the interior of the structure.

In order to obviate the necessity of incorporating metal or other anchors in the structure, for anchoring together the floor and 60 wall slabs, I provide the upper and lower surfaces of the outer edge of the floor slabs with rabbets or similar devices, which effectively accomplish the desired result. In addition to the features of construction above 65 referred to and the method of constructing buildings of slabs embodying these features, my invention includes the various other articles, combinations and steps described in the specification and more fully set forth 70 in the claim appended thereto.

In the drawing,

Figure 1 is a perspective view of a portion of my improved structure with the upper wall slab removed from the floor slab 75 for the sake of clearness;

Fig. 2 is a longitudinal section of a portion of my improved structure, showing the method of finishing the joints between the 80 wall and floor slabs;

Fig. 3 is a similar longitudinal section, but is taken through a wall at right angles to the wall of Fig. 2;

Fig. 4 is a similar longitudinal section taken at a different point in the wall illustrated in Fig. 2;

Fig. 5 is a horizontal sectional view of a portion of a wall of my improved structure, showing particularly the method of securing 85 together adjacent wall slabs.

The wall slabs shown in Fig. 1 are designated by the reference numeral 6 and the floor slab by the reference numeral 7. As shown, the floor slab 7 is rabbeted on its upper surface near the outer edge thereof at 90 8, 9 adapting it to receive the lower edges 10, 11 of the upper wall slab, as shown for instance in Figs. 3 and 4. The floor slab 7 is rabbeted on its lower surface near the exterior edge thereof at 12 to receive the 95 upper flat surface 13 of the lower wall slab. As a result of this rabbeting, it is apparent that the wall and floor slabs will be anchored together without the use of the customary metal or other anchors.

Each of the wall slabs is provided with a plurality of voids extending vertically therethrough. In the embodiment of my invention shown herein, each wall slab is provided with three such voids designated in Fig. 5 100 110

as 14, 15 and 16. It will be noted, by reference to Fig. 3, that the voids 15 are reduced or built in at the top to form the small openings 17. The purpose of this building in, 5 is to provide a more extended bearing surface for the joint between the wall and floor slabs, and form, when such holes are plugged, a surface to hold grout.

The voids 16 are not built in or reduced, 10 but are of constant cross section throughout to permit their use for finishing the joints, etc. by grouting, as will be hereinafter more fully described. Provision is made at 18 at the top of each of these voids 16 for the reception of a plate 19 for closing the void, as 15 shown in the lower part of Fig. 2.

Referring now to the floor slab 7, it will be noted that this slab is provided with a vertical void 20 adapted to be aligned with 20 one of the voids, such as the void 16 of the wall slab. The floor slab is also provided with voids 21 adapted to communicate with other voids such as 14 and 15 of the wall slabs and with voids such as 22 of the floor 25 slabs. These voids 22 of the floor slabs may run parallel either to the side or to the end walls, Fig. 2 representing, for instance, a section of an end wall, and Fig. 3 a section of a side wall.

30 Each of the wall slabs is provided on the side edges thereof with a plurality of longitudinally extending grooves adapted to cooperate with corresponding grooves on adjacent slabs. As herein shown, each slab is 35 provided with two external grooves of semi-circular cross section and a single internal groove located therebetween and of rectangular cross section. The particular number, arrangement and form of these grooves is, 40 however, obviously immaterial.

Referring now to the method of constructing a building from slabs of the general type as heretofore described, attention is directed to Figs. 1 and 2. In Fig. 1 the rabbeting 45 by means of which the wall and floor slabs are anchored together, is clearly shown. In Fig. 2 I have shown the method of grouting or finishing with cementitious material, the joints between the wall and floor slabs. In 50 accomplishing this step, I insert in the void 16 of the upper wall slab, a pipe or conveyer 25 leading from reservoir 26 which may be filled with grout or other cementitious material in a liquid state. The plate 19 is inserted at the top of the void 16 in the lower 55 wall slab to provide a surface for receiving the cementitious material which forms a bed for the floor slab. I preferably supply the cementitious material to this joint under 60 pressure. It is obvious that the material so supplied will flow along the rabbeted surfaces, both top and bottom, of the floor slab, and will thus produce a tight joint between the floor slab and the upper wall slab, as 65 well as between the floor slab and the lower

wall slab. The void 20 in the floor slab will, of course, be filled during this operation, but if it is desired to maintain any of the other passage-ways or voids open, such for instance as that indicated at 17, 21 in Fig. 3, 70 it may be done by inserting therein a plug or sprue during the grouting operation, and thereafter withdrawing it. Heretofore, in constructing buildings of this general type, it has been necessary to do a considerable 75 amount of trowel work or "buttering" by hand in an attempt to render the joints weather-proof. Experience has shown, however, that this hand operation is not only very expensive, but that it fails to produce 80 water-tight joints. The utility of my invention, which produces water-tight joints at a comparatively slight expense, is therefore obvious.

Turning now to the method of securing 85 together adjacent slabs, for example, wall slabs, reference is made particularly to Fig. 5. The grooves 23 and 24 above described co-operate with the corresponding grooves of an adjacent slab to form the voids 23^a, 24^a 90 extending longitudinally of the slabs. Certain of these voids, as herein shown the voids 23^a, I utilize for securing the slabs together by filling them with cementitious material in the liquid state. During this filling process, I use the grouting strips 28 to prevent the escape of the cementitious material from the exterior of the interior of the wall, and I insert temporarily into the void 24^a a plug or sprue 24^b to keep this void open, and to 100 also perform the function of locking the adjacent blocks in aligned position during the pouring and hardening operations. After these operations are completed, the plug 24^b is removed, leaving an open void which is 105 most useful in draining off, within the wall itself, any moisture which may, by any chance, enter the wall from the exterior, at the joint. The provision of this void 24^a thus effectually prevents any of the moisture 110 which has entered the joint from reaching the interior of the building.

The various advantages of my invention will be apparent from the foregoing. Particular stress is, however, laid upon the 115 fact that in the structure made as above described, all of the joints, whether between a wall and a floor slab or between two wall slabs, are weather-tight and water-proof and are made so by the expenditure of less labor 120 than is necessary to produce the imperfect joints now in general use. The fact that I am able to provide uninterrupted passage-ways through the wall and floor slabs for the conduction of fluids and for the installation of pipes, conduits, wires, etc., is also 125 important.

For the sake of clearness, I have described herein a single embodiment of my invention, but it is to be understood that this embodi- 130

ment has been chosen as an example of the many forms which my invention may take and that I do not wish to be limited to this particular structure, since obviously many 5 changes may be made therein, without departing from the spirit of my invention.

What I claim is:

10 A structure composed of floor slabs and wall slabs, the floor slabs being rabbeted on their upper and lower surfaces adjacent the outer edges thereof, for the reception of the lower and upper edges of the upper and lower wall slabs, said upper and lower wall

slabs being each provided with an open vertical void extending substantially throughout 15 its length, and said floor slabs being provided with a vertical void which registers with and effects communication between the voids of said wall slabs, and thereby provides an uninterrupted passage throughout 20 the wall, for the purpose of ventilation and the like.

GROSVENOR ATTERBURY.
